BENJAMIN A. MORTON, OF NEW YORK, N. Y.

TOWER CONSTRUCTION

Application filed September 26, 1928. Serial No. 308,502.

This invention relates generally to the construction of steel frame buildings, and especially such buildings as have to be erected on plots of great value, which must therefore have a large number of stories in order to make the investment worth while.

In most of our large cities where real estate values are high, there are building restrictions which require that at certain successive heights above the street level, the building must occupy, in floor plan, only a certain small proportion of the total ground floor area, whether the plot be completely filled out by the ground floor of the building or not. This renders the floor plan of series of stories at certain successive levels, progressively smaller, and when the relatively large openings necessary for the elevator shafts, air wells, stairways, piping, etc., are formed in these already small floors, a limited rentable space indeed is left.

Various arrangements of the elevator batteries, stairways, etc., have been proposed, but when an attempt is made to provide more floor space, the result has been that a substantial part of the light and ventilation are cut off. These arrangements have invariably also necessitated the employment of a considerable number of larger and more expensive structural members to take care of the peculiar and heavy "loading" on the framework the proposed arrangements entail, and these additional members make it difficult and expensive to provide in the tower walls a sufficient number, or satisfactory location, of lighting and ventilating openings, and, due to their large size and somewhat irregular locations, themselves cut off considerable light and air.

It is the chief object of the invention to provide a type of construction for steel-frame buildings whereby very tall tower buildings can be erected on small plots, which buildings will have nevertheless a considerably greater unbroken and rentable floor area than ordinary buildings of the same height and bulk, or outside dimensions, and yet can include just as many windows, shafts, and other service arrangements.

Another object of the invention is to pro-

vide a building construction of this type whereby practically all of the usual intermediate wall columns or pillars intervening between corner columns in the ordinary tower buildings can be omitted, so as to leave all the wall surfaces, from top to bottom of the towers, free for an increased number of windows or other light and air openings, thus making usable more wall space than can be provided in ordinary tower buildings of the same size, but at the same time without entailing any weakening of the framework thereby, or any other detrimental effects.

A particular object of the invention is to provide a tower building construction which will be stronger as a unitary framework and better braced against wind pressures and the like, and lower in total cost of construction, than the common tower of the same bulk and height, but nevertheless having a greater rentable floor area than an ordinary tower of the same outside dimensions, and to confer upon it notwithstanding a better appearance and a more pleasing design than is possible in ordinary steel-frame tower construction.

A few typical forms of the inventive idea are illustrated in the accompanying drawings and described hereinafter in detail, but the invention is limited in its embodiments only by the scope of the subjoined claim.

Fig. 1 is a perspective, partly broken away, of a building constructed according to the present invention;

Fig. 2 is a typical floor plan of a tower thereof, the main or base portion of the building being shown in dotted lines as occupying all of a small building plot;

Fig. 3 is a perspective detail, partly broken away, of a corner of a tower;

Fig. 4 is a detail of a modified tower construction; and

Figs. 5 and 6 are details of other modifications.

Referring now more in detail to the drawings, and particularly to Fig. 1, the present invention provides a building having a tower starting from the main body of the building—here shown as an office building—at that level at which the building, in accordance with the local building laws, must have its

floor area reduced to the minimum. In the building selected for illustration the tower occupies the center of the building with two intermediate set-backs, as illustrated at 21 5 and 22, respectively, to conform with the requirements in some localities that the tower be set back from the street. The tower may, however, be set at the corner of the building if regulations permit, or rise directly from 10 the building without intermediate set-back, if desired.

According to the present invention, the tower comprises a framework having four corner structures 2. As shown in the drawings, particularly Fig. 3, each corner structure is made up of three columns or pillars 3 spaced from each other in more or less rectangular relation in such a manner as to form a hollow pier 4, and these members 2 are extended upwardly to any desired height, as far as the main body of the tower is to extend.

The columns 3 are connected together by girders 5 at their footings on the floor of the top story of the main building, and are also 25 connected together by similar girders 5 at each successive floor level 19 thereabove. The integrity and strength of the piers 4 themselves are provided for by connecting in diagonals or tie-rods 6 to the columns 3 and 30 girders 5 between each of the floor levels 19, which members 6 also aid in resisting the torque stresses, and greatly enhance the general strength of the pier 2 as a unit, and thus 35 of the entire tower, and especially against the high wind stresses to which tall buildings are subjected.

Thus, instead of, as is usual, transmitting the entire load of all the floors and walls, etc., to continuous wall columns extending 40 from a foundation, these columns thus receiving a cumulative loading as the stories are added on, the present invention provides a structure whereby the floor and wall load of each story is supported in the piers 2 entirely 45 separately from that of the other stories, and there is thus no cumulative floor loading put upon the walls which hence may be made much lighter and of less expensive materials than ordinarily are used in towers. 50 Pillars 7 are erected as shown in Fig. 2 to connect the columns 3 to each floor to transmit the floor loading to the piers 2, and at any desired vertical intervals, girders 8, provided in the floor framework, are connected 55 to the pillars 7, the pillars 7 being themselves connected to the columns 3 by others of the girders 5.

As a result, between the corners of the tower portion of the building, no secondary or intermediate wall columns need be employed, and all the surfaces of all the side walls can be occupied by any number and arrangement of window openings desired.

In Fig. 2 the square cross sectional area of each pier 2 lies entirely without the floor

space of the tower 1, and is connected to the tower by a passageway 10 extending between the columns 7 which are common to the walls of the pier and the tower. By thus connecting the interior of the piers with the floors of the tower, all elevator shafts and fittings and the many other breaks which occur in the usual tower floor, may be removed from the floors of the tower and constructed in the piers 2, as shown at 13 in Fig. 3, where three of the piers each support and enclose a battery of two elevators outside of the floor space and tower walls and completely isolated from the tower. The fourth pier is shown as adapted and fitted to serve as a stairway well and a service piping shaft, but any other arrangements may be made without going beyond the extent of the present invention.

This arrangement of the elevators within the piers is of particular advantage from the fire hazard standpoint. By arranging a fire door as indicated at 12, across the entrance to each passage 10, any floor upon which a fire occurs may be completely cut off from the rest of the building, while leaving the stair well and elevators unobstructed for egress from the rest of the building.

In very tall towers, for example, one of the three elevator shafts may serve the lower floors only, another the middle floors only, and the other only the top floors, the space above the range of the elevators in the first two being then available for corner suites or other uses. When the floors are extended into the piers to provide additional floor space the diagonal bracing 6 shown in Fig. 3 may be omitted and a corner bracing such as shown in Fig. 6, employed, to thereby allow ample window space, as indicated.

By projecting all elevator shafts, air wells, stairways, service shafts, and the like, out from the floors they are to serve, no appreciable amount of light or air is cut off, and the total tower floor area itself, for a given height and outside dimensions of tower, is greatly increased over the ordinary total area, since all floors are left unbroken by openings of any sort.

The corner members or piers 2 of the tower are also so constructed, placed, and connected to the floor framework, as to provide an unusually high factor of safety, especially needed against the wind pressures to which tall buildings are subjected. The piers 2 are close-coupled by the floors of the tower, and hence each side of the tower acts like a vertically extending I-beam, the two piers on each opposite side corresponding to the heads or flanges of the beam, the walls connecting them oppositely corresponding to the web thereof. Thus the piers on the windward side are under tension, and those on the leeward side, under compression, and hence the piers take all such stresses from the walls

and floors of the tower, which are therefore put under neither compressive nor tensile stresses, but serve merely to maintain the piers in properly spaced relation.

5 In the modification shown in Fig. 4 the columns 3' are built in closer, and placed farther along the adjacent sides of the tower floors 14, as shown, that is, the corners of the piers 2' lie within the cross sectional area 10 of the tower proper as indicated at 14', and the side walls of the pier which join the walls of the tower do not project outwardly so far as in the first described construction.

15 The corners 15 of the piers may be made of heavy steel similar to the columns 3' and suitable fireproof partitions 16 and doors 17 may be provided at the corner structure, thereby providing fireproof corner structures lying partly within the building.

20 When a somewhat larger plot is available, and a larger tower is therefore possible, and more elevator traffic is anticipated, the structure shown in Fig. 5 can be employed to advantage. In this form, one column 3a of the 25 piers is tied in very closely to its adjacent wall 14', and another column such as 3b is tied in at a distance from its adjacent wall which depends upon the number of elevators needed in the battery. The other column 3c 30 is tied in to the first two as determined by the locations of these two. This construction also provides more space for traffic in the corners 18, and can equally as well be made fireproof, and be braced just as strongly with 35 diagonal or corner bracing or otherwise, as desired.

The piers 2" may begin at the top of the main building, the frame of the latter and particularly the girders 100 thereof serving 40 as a steel foundation for the tower structure and thus providing a greater foundation area than the area of the tower itself. If, however, the location is one where the foundations can readily be carried to bed-rock, 45 the piers may be carried down through the building, thereby permitting a lighter framework to be used for the main portion of the building.

50 The construction of the present invention provides a tower having unbroken floors of fully rentable area with all its walls available for windows, and yet of strong unitary construction and better braced against wind and other stresses, though having a smaller 55 number of structural parts, than ordinary towers of the same outside dimensions. In case this building catches on fire, the shafts may be entirely isolated from the tower though forming a structural part thereof, 60 and the fire hazard is thus considerably reduced, materially enhancing the value of the building. By the loading and unloading of the elevators outside of the floor space proper, the noise, annoyance and traffic congestion of the ordinary building are removed 65

from the main office space and isolated from the building, and the employment of this form of construction obviously results in improving the appearance of tower buildings, and provides a new architectural design for 70 office and other tall buildings.

I claim:

A steel frame building comprising a main lower portion and a tower portion comprising a plurality of floors and walls supported in vertical arrangement upon said lower portion at their corners only, by a plurality of vertical members outside the walls and floors of said tower portion said vertical members being spaced from each other and united to 75 the floors in such a manner as to constitute shafts for servicing the tower, said shafts constituting the only vertical structural members in the tower frame work.

In testimony whereof I affix my signature. 80
